United States Patent

Des. 241,724

Patented Oct. 5, 1976

241,724

CLOCK

Shirley Ann Bartlett, 717 Park Drive,
Hillsboro, Tex. 76645

Filed Mar. 17, 1975, Ser. No. 558,774

Term of patent 14 years

Int. Cl. D10—01

U.S. Cl. D10—11

FIG. 1 is a front elevational view of a clock showing my new design, the bottom and rear views being substantially flat, plain, and unornamented;

FIG. 2 is a left side elevational view thereof as taken from line 2—2 of FIG. 1, the right side being substantially identical thereto.

I claim:

The ornamental design for a clock, as shown and described.
